(57) **CLAIM**

The ornamental design for a display panel or screen with an animated graphical user interface, as shown and described.

DESCRIPTION

FIG. 1 is a front view of a first embodiment of a display panel or screen with a first image of an animated graphical user interface showing my new design;

FIG. 2 is a front view thereof with a second image;

FIG. 3 is a front view thereof with a third image;

FIG. 4 is a front view thereof with a fourth image;

FIG. 5 is a front view thereof with a fifth image;

FIG. 6 is a front view thereof with a sixth image;

FIG. 7 is a front view thereof with a seventh image;

FIG. 8 is a front view thereof with an eighth image;

FIG. 9 is a front view thereof with a ninth image;

FIG. 10 is a front view thereof with a tenth image;

FIG. 11 is a front view thereof with an eleventh image;

FIG. 12 is a front view thereof with a twelfth image;

FIG. 13 is a front view thereof with a thirteenth image;

FIG. 14 is a front view thereof with a fourteenth image;

FIG. 15 is a front view thereof with a fifteenth image;

FIG. 16 is a front view thereof with a sixteenth image;

FIG. 17 is a front view thereof with a seventeenth image;

FIG. 18 is a front view thereof with an eighteenth image

FIG. 19 is a front view thereof with a nineteenth image;

FIG. 28 is a front view thereof with a twenty-eighth image;

and,

FIG. 29 is a front view thereof with a twenty-ninth image.

(Continued)

The appearance of an image sequentially transitions between FIGS. 1-29. The process or period in which an image transitions to another forms no part of the claimed design. The even dashed broken line showing of a display panel or screen and portions of the graphical user interface form no part of the claimed design.

The dot-dash and dot-dot-dash broken lines define the bounds of the claimed design and form no part thereof.
